UNITED STATES PATENT OFFICE.

JOSEPH PODUFALY, OF DETROIT, MICHIGAN.

AUTOMOBILE-LOCK.

1,308,298.

Specification of Letters Patent. Patented July 1, 1919.

Application filed December 4, 1917. Serial No. 205,415.

To all whom it may concern:

Be it known that I, JOSEPH PODUFALY, a subject of the Emperor of Austria, resident of Detroit, county of Wayne, and State of Michigan, have invented certain new and useful Improvements in Automobile-Locks, of which the following is a specification.

This invention relates to improvements in locks and particularly to types adapted to 10 be applied to automobiles, the locks being of a permutative character.

The principal object of the invention is to provide a lock difficult to operate except to one familiar with the combination. A 15 further object is to provide means whereby the several combinations may be readily changed.

These and other like objects are attained by the novel construction and combinations 20 of parts, hereinafter described and shown in the accompanying drawings, forming a material part of this specification, and in which—

Figure 1 is a front elevational view showing a lock made in accordance with the invention.

Fig. 2 is a vertical sectional view taken on line 2—2 of Fig. 1.

Fig. 3 is a vertical sectional view taken 30 on line 3—3 of Fig. 2.

Fig. 4 is another similar sectional view taken on line 4—4 of Fig. 2, and

Fig. 5 is a fragmental perspective view showing a detail used in construction.

Fig. 6 is a detail view of one of the lugs 35 and its beveled surfaces.

The invention comprises a substantially rectangular casing, having a solid back 10, joined to the floor or bottom plate 11 and 40 to the cover or top plate 12, and the rigid ends 13, and 14.

The entire front of the casing is normally covered by a plate 15, pivoted at its bottom on a rod 16, while at the top is 45 mounted a relatively narrow casing 18, containing a circular opening normally covered by transparent plates 19, through which a target 20 can be seen when in a raised position, the same being supported by a flat 50 stem 21, pivoted upon the screw 22, within the main portion of the casing.

An angularly disposed, flat extension 23 of the flat stem 21 contains a longitudinal slot 24, engaging with a pin 25, rigidly set in a plate 28, slidable longitudinally within 55 the casing in slotted guides 29 secured to the top and bottom of the casing, stops 30, and 31 being formed with the plate.

In Fig. 3 the target is shown in dotted lines in its lowered positions. 60

Motion is communicated to the plate by an extending handle 35, bent at a right angle and operable within a slot 36, formed in the hinged plate 15. This plate 15 is operable by means of a knob 40, attached to the inner 65 end of which is a bent latch 41, engageable in a transverse groove formed in the lower side of the handle 35, so as to lock the same when in an adjusted position in connection with a lug 42 received in a recess 43, in a 70 projection 44, formed on plate 15.

Formed in the plate 15 are a plurality of openings 45 through which extend push buttons 46, the same having collars 47, upon their inner sides, adapted to make contact 75 with the inner surface of the said plate and which are normally pressed against it by compression springs 48, the other ends of which abut against the fixed brackets 49, secured to the inner side of the plate 15. 80

These push buttons are arranged in two rows and are spaced equally apart as will be best seen in Fig. 1. Contactable with push buttons are cylindrical plungers 52, the same being supported in a fixed vertical 85 plate 54, secured by feet 55 to the bottom and top walls of the container, and through which is a slotted opening 56 for the handle 35 to operate. All of these several plungers 52 are also supported by another plate 58, 90 spaced outwardly from the rear wall 10 by means of washers or collars 59, while the extending ends of the plungers are pressed normally outward by bent flat springs 60, as can best be seen in Fig. 2. 95

Secured to the outer face of the plate 54 are a pair of parallel guides 63, the same having undercut portions which receive corresponding tenons formed with a sliding bar 65, drawn normally rearward against 100 the stop 66, by means of tension spring 67, the bar having a longitudinal undercut slot

- 70, suited to the heads 71, of bolts 72, provided with winged nuts 73, by means of which transverse blocks 75, may be rigidly clamped to the bar. These blocks 75, are 5 formed with extending ends 77 having angular upper surfaces and may be secured in any adjustment along the bar 65 in accordance with index numerals 79 on its surface. Three of the movable blocks are used, the arrangement being such that the extending beveled ends 77 are clear of the plungers 52, each of which is provided with projecting lugs 80 having similar but oppositely beveled surfaces.
- 10 Each of the plungers 52 are grooved upon their sides in such manner as to form two flat spaces 82 and 83, the same being fitted to slide in longitudinal slots 85 formed in the plate 28 so as to permit the plate to slide 15 without interference with the plungers when the latter are positioned to allow such movement.

20 Cranks 86 are formed with the plungers, the same being slotted and having engaged therein links 88, extending upward normally to a uniform height and bent outwardly forming handles 90, extending through slots 92 in the stationary plate 54, in such manner that when the handles 90 are 25 raised or lowered, the plungers 52 are turned 30 correspondingly.

35 A lever 94 is pivoted near one end of the case upon a pin 95 and is provided with a hook or catch 96 engageable with the handle 35, by means of the spring 98, one end of which is secured to plate 54, and the other to the longer limb 99 of the lever, which also carries an extending pin 100 contactable with the front end of the slide bar 65, so as 40 the same is advanced, the hook is caused to 45 release the handle.

Movement is transmitted through the slide bar 65 to the hook in the following manner: The drawings show two uniform 45 rows of push buttons 46, which engage operatively with the plungers 52, pressing the same inward, causing the beveled faces of the lugs 80 to engage with the correspondingly beveled ends 77 of the transverse blocks 75, three of which are used and which have been clamped with relation to the index 79 in any desired relation.

Let it be assumed that, as shown, the first block to the left is adjacent to numerals 55 1 in the second index, the second block adjacent to the numerals 2 in the third index, the fourth row left blank and the third block arranged with relation to the numeral 3 in the last index, the handle 90, corresponding 60 to the push button B, is raised, the plunger is in position to permit plate 28 to be slid, and the handles corresponding to the characters H and J are raised and are so set as to admit the corresponding buttons to be 65 pressed in and cause the lugs 80 to make con-

tact with the bevel ends 77. The plungers, other than the active ones, will prevent plate 28, from sliding if either one of said plungers is operated.

The buttons however must be pressed in proper sequence as for instance the button B upon being depressed moves the alined plunger inward, forcing its lug against the block clamped on the bar 65 so as to cause a tooth 105, formed on said bar to engage with the first tooth in a ratchet 106, formed upon an extended portion of a pawl 108, pivoted on the screw 109, and held in an engaging position by the spring 110 and having a stem 111, passing through a slot 112 as can be seen in Fig. 4.

Let it now be assumed that the handle corresponding with the push button H is in a raised position, whereupon its depression moves the alined plunger inwardly and forces its lug against the block which will bring the inclined surface of the last named block in register with the lugs on the plunger corresponding to the push button J which upon being pushed inward causes the slide 85 bar 65 to move the lever 99 to such an extent as to release the catch 96 from the handle 35 thereby permitting it to be pushed to the right and the plate 15 opened, so that access 90 may be had to the interior of the casing.

From the foregoing it will be obvious that a wide range of combinations can be made by merely moving the blocks 75 to various positions along the slide bar 65, the number of combinations being increased by arrangement of the handles 90.

Having thus described my invention what I claim as new and desire to secure by Letters Patent, is—

1. In a lock, the combination with a casing and a plate normally covering the front thereof, of a rigid vertical plate secured centrally in said casing, a plate parallel thereto and movable longitudinally within said casing, a slide bar mounted on said rigid plate 105 to move longitudinally of said casing, means for normally maintaining said bar in one position, a tooth formed on said bar, a pawl pivoted in said casing, a plurality of teeth 110 formed on said pawl engaging with said tooth, means for pressing said teeth normally in engagement, a knob and a grooved handle carried by said plate, a bent latch attached to the inner end of said knob engaging the groove in said handle for holding 115 said plate in a normally closed position, for limiting the movement of said sliding plate, a lever engaged with and operable by said slide bar, and means for progressively actuating said slide from the exterior of said 120 cover plate.

2. In a lock, the combination with a casing, a hinged plate for said casing, a plurality of push buttons extending therethrough, plungers engageable with said push 130

buttons, a slide having an extending handle engageable with said plate a knob and a grooved handle, carried by said plate, a bent latch attached to the inner end of said knob

5 engaging the groove in said handle for holding said plate in a locked position, means for rotating said plungers into an operative po-

sition, a slide bar movable in said casing, and flat portions on said plungers for operating said slide bar in a predetermined manner for releasing said plate. 10

In testimony whereof I have affixed my signature.

JOSEPH PODUFALY.
